(57) **CLAIM**

The ornamental design for a shelf supporter for refrigerator, as shown and described.

DESCRIPTION

FIG. 1 is a perspective view of a shelf supporter for refrigerator, showing our new design;
FIG. 2 is a front view thereof;
FIG. 3 is a rear view thereof;
FIG. 4 is a side view thereof;
FIG. 5 is a another side view thereof;
FIG. 6 is a top view thereof;
FIG. 7 is a bottom view thereof; and,
FIG. 8 is another perspective view thereof, in use condition.
The broken lines are for environmental purpose only and form no part of the claimed design.
